(57) **CLAIM**

I claim the ornamental design for the gemstone ring, as shown and described.

DESCRIPTION

FIG. 1 is a front view of the gemstone ring;

FIG. 2 is a side view of the gemstone ring;

FIG. 3 is a top view of the gemstone ring;

FIG. 4 is a bottom view of the gemstone ring; and,

FIG. 5 is a perspective top view of the gemstone ring.

The broken lines shown in the drawings illustrate portions of the gemstone ring which form no part of the claimed design.
